UNITED STATES PATENT OFFICE.

HENRY J. PIERSON, OF KEENE, NEBRASKA.

SPRING SEAT.

Application filed September 10, 1924. Serial No. 736,903.

This invention relates to spring seats for farm machinery, such as tractors, wheeled cultivators and the like, and has for its principal object to provide a means whereby 5 the operator of the machinery may obtain a maximum comfort occupying the seat.

Another important object of the invention is to provide a spring seat of the above mentioned character wherein means is provided for limiting the upward movement of the seat, as well as limiting the downward movement thereof.

Another important object of the invention is to provide a spring seat of the above mentioned character, which is simple in construction, inexpensive, strong and durable, and further well adapted for the purposes for which it is designated.

Other objects and advantages of this invention will become apparent during the course of the following description.

In the accompanying drawing, forming a part of this specification, and in which like numerals designate like parts throughout 25 the same:

Figure 1 is a side elevation of the spring seat embodying my invention.

Figure 2 is a top plan view thereof with the seat removed, and

30 Figure 3 is a sectional view, taken approximately on the line 3—3 of Figure 1.

In the drawing, wherein for the purpose of illustration is shown the preferred embodiment of my invention, the numerals 1 and 2 designate a pair of vertically spaced horizontally arranged plates, each of which is of substantially rectangular design, the lower plate 2 being adapted to be secured on the upper end of the seat supporting beam 3 by any suitable fastening means, such as is shown at 4. The upper plate 1 is adapted to be secured on the bottom of the usual seat 5, in any suitable manner.

45 Disposed between the spaced upper and lower plates are the helical coil springs 6. The springs are arranged on each of the sides of the plate, one spring being provided for each of the sides and the same being arranged centrally, or intermediate the ends, 50 in a manner as more clearly illustrated in Figures 1 and 3 of the drawing. The helical coil springs are spaced inwardly from the side edges of the plate and secured at their respective ends to the upper and lower

plates respectively, adjacent the helical coil 55 springs 6 of the chains 7. The provision of the chains 7 is to provide a means for limiting the upward movement of the plate 1 and seat 5 carried thereby.

For the purpose of limiting the downward movement of the plate 1 and seat 5 secured thereto, bumpers, such as are shown at 8, are arranged at the corners of the lower plate 2, and extend upwardly for a suitable distance, in the manner as more 65 clearly illustrated in Figure 1.

In order to prevent any sidewise movement of the upper plate and seat secured thereto, with respect to the lower plate 2, the diagonally arranged coil springs 9 and 10 are secured at their lower ends to the plate 1, as at 11, while the upper ends of the diagonally extending coil springs are secured to the upper plate 1, on opposite sides of each of the corners thereof.

75 It is of course to be understood that the diagonally arranged coil springs are arranged at each of the corners of the plate, in the manner as shown in the drawing.

The provision of a spring seat of the above mentioned character, for use in connection with farm machinery, will enable the operator of the machinery to be seated comfortably thereon. The springs will at all times be positive and efficient in their 80 operation.

85 While I have shown the preferred embodiment of my invention, it is to be understood that various changes in the size, shapes, and arrangement of parts may be 90 resorted to without departing from the spirit of the invention or the scope of the claim.

Having thus described my invention, 95 what I claim as new is:

In a spring seat structure, a pair of vertically spaced horizontally disposed plates, spring means holding said plates normally in their spaced relationship, a plurality of chains attached to the plates for limiting the distance therebetween, a plurality of springs having their upper ends connected to the upper plate at its edge and their lower ends attached to the lower plate at points spaced inwardly from its edge.

100 105 In testimony whereof I affix my signature,

H. J. PIERSON.
